JOINT GLUING MECHANISM IN A BOOK
CASING-IN MACHINEJames H. Thorp, West Hartford, Conn., assignor to The
Smyth Manufacturing Company, Bloomfield, Conn., a
corporation of ConnecticutFiled Sept. 17, 1964, Ser. No. 397,202
10 Claims. (Cl. 118—227)

This invention relates to book casing-in machines of the type wherein book fillers are successively fed toward a casing-in station to be mated with a bookcase or cover, and deals more particularly with a mechanism for gluing the joints of such fillers. The general type of machine and gluing mechanism referred to is more completely shown and described in my co-pending application, Ser. No. 157,109, entitled, "Apparatus for Use With a Casing-In Machine," filed Dec. 5, 1961.

The general object of the present invention is to provide an improved joint gluing mechanism for a casing-in machine wherein fillers of a minimum vertical height can be accommodated as a result of a novel arrangement of various parts of the joint gluing mechanism.

A more specific object of the invention is to provide a joint gluing mechanism for a casing-in machine wherein two oppositely arranged rollers are continuously driven in a common generally horizontal plane and are movable in the plane toward and away from the filler to be glued.

Still another object of the invention is to provide a joint gluing mechanism for a casing-in machine wherein the rollers for applying glue to the joints of a filler are movable toward and away from the filler without interrupting the application of a continuous coating of glue thereon.

The drawing shows a preferred embodiment of the invention and such embodiment will be described, but it will be understood that various changes may be made from the construction disclosed, and that the drawing and description are not to be construed as defining or limiting the scope of the invention, the claims forming a part of this specification being relied upon for that purpose.

Of the drawing:

FIG. 1 is a plan view of a joint gluing mechanism constructed in accordance with the present invention; and

FIG. 2 is a side elevational view partly in section of the FIG. 1 mechanism.

Referring now to the drawing in greater detail, FIG. 2 shows a joint gluing mechanism 10 adapted to be installed on a casing-in machine (not shown) by two arms 12, 12 attachable at their lower ends to the frame of the machine. Such a machine is fully shown and described in the aforementioned co-pending patent application and need not be described herein. As best shown in FIG. 1, such a machine is adapted to feed fillers of the type indicated at 14, generally horizontally and longitudinally in the direction of the arrow 16. In a machine equipped with a mechanism of the present invention, the fillers are fed below an elongated bed, indicated generally at 18, which extends transversely above and across the path of filler movement as shown in FIG. 2.

The bed 18 comprises a pair of parallel guide rods 20, 20 the ends of which are fixedly attached to the upper portions of the arms 12, 12 by nuts 22, 22 threadably received on the ends of said rods. Also provided in the bed 18 is a splined shaft 24 rotatably supported adjacent its end portions in two bearings 26, 26 defined in the upper portions of the arms 12, 12. As shown in FIG. 1, the splined shaft 24 is driven by a drive shaft 28 arranged at right angles thereto and having a bevel gear 30 which meshes with a similar gear 32 on the shaft 24. While the shaft 24 may be made in one piece, in the construction shown two splined segments are preferably joined end to end by a collar 34.

2

Left- and right-hand carriages, 36 and 38 respectively, are slidably supported on the guide rods 20, 20 and means are provided for reciprocably moving the carriages horizontally toward and then away from the longitudinal path of movement of the fillers. In the description to follow only the left-hand carriage 36 will be described in detail, it being understood that the right-hand carriage 38 is substantially identical thereto. As shown the means for moving the left-hand carriage 36 comprises a rack segment 40 slidably received in the left-hand arm 12 and connected to the left-hand carriage 36, and a gear segment 42 which is pivotally mounted on the upper portion of the left-hand stationary arm 12 for reciprocably moving the said rack segment. The gear segment 42 is adapted to be oscillated by a push rod 44 connected at its upper end to an arm 46 on the gear segment and at its lower end to a convenient drive means in the casing-in machine. Such drive means operates the push rod in timed relationship with the movement of fillers between the left- and right-hand carriages 36 and 38 respectively. The right-hand carriage 38 is movable in an opposite direction and in unison with the left-hand carriage 36 by the operation of a corresponding right-hand push rod 48.

Turning now to a more detailed description of the left-hand carriage 36, FIG. 1 shows this part of the joint gluing mechanism as comprising transversely spaced inner and outer slide blocks, 50 and 52 respectively, each of which defines two parallel openings for receiving the guide rods 20, 20. As shown in FIG. 2, the slide blocks 50 and 52 are connected at their lower ends to a drip pan 54 which is of shallow depth to allow the mechanism for feeding fillers (not shown) to pass therebeneath. In prior joint gluing mechanisms, the vertical space required for the glue roller and its associated reservoir has restricted the use of automatic casing-in machines to gluing relatively high fillers. It will be apparent that the shallow drip pan 54 shown occupies only a bare minimum of vertical space allowing fillers of substantially any vertical height to be glued.

In order to reduce still further the height of the carriage 36, a horizontally arranged glue applying wheel, or roller, 56 is provided above the drip pan 54. An L-shaped arm 58 is integrally provided on the inner slide block 50 and rotatably supports a pair of meshing bevel gears 60 and 62 for driving the roller 56. The gear 60 has internal flutes which mesh with the splined shaft 24 to transmit the rotational movement of the shaft to the gear 60 without limiting translational movement of the gear 60. The gear 62 is attached to a vertically arranged stub shaft 64 which is rotatably received in the lower part of the arm 58 and carries the roller 56. As so constructed the roller 56 is continuously driven in the direction indicated by the arrow 66 so long as the splined shaft 24 is rotated. A counter-rotating glue roller 68 in the right-hand carriage 38 is similarly driven in the direction of the arrow 70. It will be apparent that the peripheral speed of these rollers can be adjusted to substantially conform to the lineal speed of the filler being glued by conventional means associated with the drive shaft 28 and with the mechanism for feeding fillers through the machine (not shown).

The outer slide block 52 is connected to the above mentioned rack segment 40 by an adjusting screw 72 which is threadably received in an opening in the rack segment 40. The inner end of the screw 72 is slidably received in an opening in the outer block 52 and outer and inner nuts, 74 and 76 respectively, secure the screw 72 to the block 52 for movement therewith. A compression spring 78 is preferably provided between the block 52 and the outermost nut 74 to permit a predetermined degree of over travel of the screw 72 and to provide a uniform force between the filler 14 and the rollers 56.

and 68. An adjusting knob 80 allows the screw 72 to be pre-adjusted in the rack segment 40 so that fillers of various thicknesses can be accommodated but the actual travel of the carriages 36 and 38 is determined by the movement of the arms 44 and 48.

A glue reservoir other than the drip pan 54, is defined by appropriate housing means 82 in the machine and is preferably located below the mechanism just described as shown in FIG. 2. In the embodiment shown, glue is pumped from the reservoir by a suitable pump, indicated generally at 84, through flexible conduits 86 and 88 to the left- and hand-hand carriages, 36 and 38 respectively. The end portions of the conduits 86 and 88 are clamped to the carriages and the shut-off valves 90 and 92 are provided thereat so that the flow of glue onto each roller can be appropriately metered. As best shown in FIG. 2, the ends of the conduits are preferably so arranged that the glue is deposited on a beveled face, 94 and 96, at the periphery of the rollers, 56 and 68 respectively. Preferably and as shown, the glue is deposited on the roller 56 at roughly the opposite side thereof from that engaged by the filler 14 and it is usually desirable to locate the end of the conduit 86 slightly ahead of this position with respect to the direction of rotation of the roller to assure that some glue flows downwardly off the beveled face 94 and onto the vertical edge portion 95 of the roller's periphery. In this manner glue will be deposited both on the joint area of the fillers and on a portion of the vertical sides adjacent thereto.

It will, of course, be apparent that the operation of the push rods 44 and 48 can be so timed that the rollers 56 and 68 engage each filler shortly after the leading end of the filler has passed therebetween and disengage from the filler shortly before the trailing end reaches the rollers. In this manner small unglued areas are left at the ends of the filler and the tendency of the glue to overflow onto the end faces thereof is avoided. Suitable mechanism for so operating rods such as 44 and 48 is shown and described in the aforementioned patent application and therefore need not be described in detail herein.

In order to control the thickness of the glue deposited on the filler 14 suitable scraper means are provided on the carriage 36. As shown, said means includes a first radially extending arm 98 integrally connected at its inner end to the inner slide block 50. The outer end of the arm 98 extends some distance beyond the periphery of the roller 56 and carries a plurality of individually adjustable scraper elements 100, 100 which can be preset to control the width and thickness of the film of glue on the roller 56. Excess glue is thus scraped off the roller and into the drip pan 54.

Preferably and as shown, the glue in the drip pan 54 is drained back into the reservoir 82 by a return conduit 106 connected to a port in the pan 54 and to a second pump 108 at the reservoir.

While not required in all installations, a second radially extending arm 102 is provided ahead of the open end portion of the conduit 86 and carries a second scraper element 104 for removing any glue on the roller 56 which fails to be deposited on a filler. In this manner, the roller 56 can be continuously provided with a fresh film of glue, the drip pan 54 serving to recapture any glue removed by the scraper 104. It has been found with certain types of fast setting glue that such a secondary scraper may be required in order to prevent congealing of the glue on the roller.

In accordance with the present invention, a continuous flow of glue is maintained both to and from the rollers 56 and 68 by the conduits 86, 88 and 106, 106 respectively, more glue being delivered to these rollers than is required for gluing a filler. The pumps 84 and 108 maintain a continuous circulation of the glue in order to prevent premature congealing or setting up of the glue especially in the drip pans themselves where the glue would otherwise remain in prolonged contact with the atmosphere. It is an important feature of the present in-

vention that the reservoir 82 is provided as a separate glue receptacle which may be quite remote from the drip pans adjacent the glue applying rollers 56 and 68. As so arranged, the pans can be quite shallow to permit fillers of all sizes to be accommodated in a casing-in machine equipped with a joint gluing mechanism of the present invention.

The invention claimed is:

1. In a casing-in machine which includes mechanism for feeding fillers toward a casing-in station wherat cases are mated with the fillers, the improvement comprising glue reservoir defining means, a pair of horizontally opposed glue rollers each of which is rotatably mounted at one side of the longitudinal path of movement of said fillers for rotation about vertical axes, each of said glue rollers having a peripheral contour which conforms in vertical section generally to the relatively narrow joint area of the filler to be glued, conduit means for continuously delivering glue from said reservoir to each of said rollers, means for rotating said rollers, means for moving said rollers in opposite directions generally horizontally toward and away from said filler path and in timed relationship with the movement of fillers therewith, and a shallow drip pan below each of said rollers, said drip pans being in communication with said glue reservoir defining means so that glue in said pans is returned to said reservoir.

2. In a casing-in machine which includes mechanism for feeding fillers longitudinally toward a casing-in station wherat cases are mated with the fillers, the improvement comprising glue reservoir defining means, an elongated bed supported in the fixed frame of the machine and extending transversely above and across the longitudinal path of movement of said fillers, two carriages slidably mounted on said bed, a glue roller rotatably supported in each of said carriages, conduit means for continuously delivering glue from said reservoir to each of said rollers, means for rotating said rollers, and means for moving said carriages along said bed in opposite directions toward and away from the said filler path and in timed relationship with the movement of fillers therewith so that rollers move into filler engaging positions after the leading edge of the filler to be glued has been fed therewith and move away from said position before the trailing end of the filler reaches said roller.

3. In a casing-in machine as set forth in claim 2 wherein each of said rollers is supported in its associated carriage for rotation about a vertical axis and has a peripheral portion which includes a beveled face adapted to receive glue from said conduit means and to engage the joint of the filler to be glued.

4. In a casing-in machine as set forth in claim 3 and further characterized by a glue scraper means located in closely spaced relation to the beveled face of each roller to form a film of glue of controlled thickness thereon.

5. In a casing-in machine which includes mechanism for feeding fillers generally longitudinally toward a casing-in station wherat cases are mated with the fillers, the improvement comprising a glue reservoir defining means, an elongated horizontal bed supported in the frame of the machine and extending transversely above the longitudinal path of movement of said fillers, two carriages slidably on said bed, means for moving each of said carriages a fixed distance in opposite directions along said bed, two rollers rotatably supported respectively in said carriages for rotation in a common horizontal plane, a splined shaft rotatably supported at opposite ends in said bed and adapted to be continuously driven as said fillers are fed, gear means between said splined shaft and said rollers for rotating the latter in opposite directions and at a peripheral speed at least approximately equal to the lineal speed at which said fillers are fed, conduit means for continuously delivering glue from said reservoir to the peripheral portions of said rollers, a shallow drip pan below each of said rollers, return conduit means connected to said pans and to said glue reservoir, and pump

means at said reservoir for maintaining a continuous circulation of glue in said conduit means to prevent setting up of the glue in said drip pans.

6. In a casing-in machine as set forth in claim 5 and further characterized by manually operable adjusting means for presetting the position of said carriages on said bed whereby fillers of various thicknesses can be glued in the area of their joints,

7. In a casing-in machine as set forth in claim 5 wherein in each of said rollers has a beveled peripheral upper face for receiving the glue delivered thereto by said conduit means, which beveled face also engages a portion of the filler to be glued, and two open ended portions of said conduit means each of which is clamped to one of said carriages to deliver the glue to its associated roller at a portion on the periphery thereof which is generally diametrically opposed to that portion which engages the filler.

8. In a casing-in machine as set forth in claim 7 wherein each of said rollers has a vertical peripheral edge portion below said beveled face for depositing glue on a vertical portion of the filler adjacent the joint area thereof.

5 9. In a casing-in machine as set forth in claim 8 and further characterized by glue scraper means carried by each of said carriages, said means including at least one

scraper element adapted to be located in closely spaced

relation to the beveled face of each of said rollers to

regulate the thickness of the film of glue thereon before

said film is deposited on the filler.

10 10. In a casing-in machine as set forth in claim 9 wherein in each of said glue scraper means includes a secondary

scraper so located in said carriage as to scrape sub-

stantially all excess glue from said roller.
